Filed Mar. 12, 1971, Ser. No. 123,941

Term of patent 14 years

Int. Cl. D14—03, 99

U.S. Cl. D26—1

FIG. 1 is a front perspective view of a combined magnifier and radio tuning indicator, showing my new design;

FIG. 2 is a front perspective view of a modified embodiment of the tuning indicator illustrated in FIG. 1; and

FIG. 3 is a front perspective view of a further modified embodiment of the tuning indicator illustrated in FIG. 1.

The broken lines representing the radio are shown for illustrative purposes only.

What I claim is:

The ornamental design for a combined magnifier and radio tuning indicator, substantially as shown and described.
